UNITED STATES PATENT OFFICE

2,653,726

CLOSURE FOR UNREFILLABLE CONTAINERS

Ricardo More Bernal, Havana, Cuba

Application December 4, 1951, Serial No. 259,839
In Cuba December 23, 1950

2 Claims. (Cl. 215—22)

1

This invention relates to closures for unrefillable containers, and particularly to closures of that kind which are provided with a ball above the valve so as to force the valve to remain on its seat thereby preventing the entrance of liquid into the container or bottle.

The object of this invention is to provide a closure of the ball type which comprises a valve-carrier body which is almost completely inserted within the bottle neck and has a plane seat provided with a lower axle-box supported on four oblique depending arms and whose function is to serve as a guide for a vertical pin inferiorly secured to the plane valve, the valve-carrier body having lodged therein a loose glass ball which rests by its own weight on the plane valve, and the valve-carrier body has an upper rim of greater diameter than the very valve-carrier body to form an annular projection the horizontal base of which rests upon the inner portion of an annular packing resting on the top edge of the bottle.

The closure of this invention also comprises a rather short cylindrical casing the lower edge of which rests on the outer portion of the annular packing and the upper portion of which has a raised central mouth for liquid discharge from the bottle, and the top portion of the casing has interiorly thereof in crossed arrangement four radial horizontal ribs ending interiorly in four sloped teeth with recesses at the inner end of the ribs and at the inner cylindrical surface of the mouth; a hard-metal square sheet interposed by its points between the upper edge of the projecting rim of the valve-carrier body and the lower face of the four radial ribs projecting downwardly from the lower face of the top plane portion of the casing to allow between the straight sides of the sheet and the inner cylindrical surface of the casing body four segment-of-a-circle spaces for the passage of inner liquid from the bottle towards the casing mouth, said hard-metal sheet having four crossed openings wherethrough fit the four downward projecting teeth of the casing, and the openings of the sheet being provided at their inner edge with raised lugs adapted to fit into the inner vertical recessed ends of the four horizontal ribs of the casing and the mouth inner surface with which said lugs are adapted to flush; and a strap that inviolably secures the casing to the bottle neck thereby forming a closure device in which the outward passage of the liquid is prevented at the central portion that is obturated by the metal sheet which only provides four peripheral passageways through which an instrument such as a wire can hardly be inserted towards the valve for the purpose of holding the latter open and thereby refilling the bottle or container with a liquid of inferior quality, whereupon this closure is efficient against violations.

The invention is described with reference to the figures of the accompanying drawing, of which:

2

Fig. 1 is a diametral vertical section view of the closure of this invention, showing the closure applied to the mouth of a bottle neck in vertical position.

5 Fig. 2 is a horizontal section view on line 2—2 of Fig. 1, viewed from beneath.

Fig. 3 is a detailed view, partly in elevation and partly in diametral vertical section, of the closure valve-carrier body.

10 Fig. 4 is a bottom plane view of the valve-carrier body.

Fig. 5 is a detailed view, partly in elevation and partly in diametral vertical section, of the closure casing.

15 Fig. 6 is a bottom plane view of the casing.

Fig. 7 is a top plane view of the square hard-metal sheet interposed between the casing and the valve-carrier body.

Fig. 8 is a vertical section on line 8—8 of Fig. 7.

20 Fig. 9 is a similar view to that of Fig. 1, showing the bottle neck with the closure in an inclined position to pour the inner liquid from the bottle.

Fig. 10 is a similar view to that of Fig. 1, showing a modified form of the closure casing, the same forming the strap to inviolably secure the closure to the bottle neck.

25 Fig. 11 is a detailed view, partly in elevation and partly in diametral vertical section, of the modified form of the closure casing.

In the drawings, 1 indicates a bottle neck having an outer shoulder 2 at its top end portion and the inner diameter of which shall be slightly greater than that of the neck of the bottles commonly used for containing alcoholic beverages or liquors, so that it can easily lodge therein for the discharge of liquid 3 from the bottle in an amount nearly equal as in a common bottle, a valve-carrier cylindrical body 4 made of plastic material and having at its top edge a horizontal annular flange 5 bent upwards at a right angle to form a projecting rim 5' of greater diameter than the valve-carrier body 4, the annular flange 5 being adapted to rest on the inner portion of an annular packing 6 superposed to the top edge of the bottle neck 1. The valve-carrier body 4 thus remains lodged almost completely within the bottle neck 1 and it has inferiorly a horizontal bottom 7 provided with a central opening 8 that is normally obturated by a plane disc valve 9 resting on the bottom 7, said valve being provided with a downwardly projecting central pin 10 which is guided in its movement to and from engagement with its seat within a vertical axle-box 11 formed vertically beneath the central portion of opening 8 by four spaced apart arms 12 obliquely depending in a circle from the bottom 7 serving as a seat for the plane valve 9.

30 Upon the plane valve 9 loosely rests a glass ball 13 which in the normal vertical position of the bottle 1 forces by gravity the valve 9 to rest upon its seat, thereby keeping the opening 8 closed.

35 Fig. 2 is a horizontal section view on line 2—2 of Fig. 1, viewed from beneath.

40 Fig. 3 is a detailed view, partly in elevation and partly in diametral vertical section, of the closure valve-carrier body.

45 Fig. 4 is a bottom plane view of the valve-carrier body.

50 Fig. 5 is a detailed view, partly in elevation and partly in diametral vertical section, of the closure casing.

55 Fig. 6 is a bottom plane view of the casing.

60 Fig. 7 is a top plane view of the square hard-metal sheet interposed between the casing and the valve-carrier body.

This closure has a cylindrical casing 14 made of plastic material and open at the bottom and closed on top by a horizontal portion having a central opening 15 on the edge of which is raised a cylindrical mouth 16 adapted to be closed by an inner cork stopper or an outerly fitting plastic cover, and the casing 14 rests by its inner edge on the outer portion of the annular packing 6 adjacently the top projecting rim 5' of the valve-carrier body 4. Said casing 14 is provided at the inner face of its top horizontal portion with four rather thick crossed radial ribs 17 ending inferiorly in channeled recesses 18 formed also vertically at the inner cylindrical surface of the mouth 16 for the purpose that will be presently explained, and from the inner ends of the four ribs 17 downwardly project vertical teeth 19 having their inner face outwardly sloped to guide and retain the ball 13.

Between the lower face of the four crossed radial ribs 17 and the top edge of the projecting rim 5' of the valve-carrier body 4 is interposed a hard-metal sheet 20 of square shape (Fig. 7) which rests by its points on the top edge of the projecting rim 5' and has four square openings 21 spaced apart from one another in crossed arrangement, the inner end of which end in raised lugs 22.

The openings 21 are adapted to receive therethrough the four teeth 19 downwardly projecting from the inner ends of the ribs 17, the raised lugs 22 being adapted to remain lodged within the vertical channeled recesses 18 formed in the inner surface of the raised mouth 16 with the inner surface of which the inner faces of the lugs 22 flush.

The casing 14 is inviolably secured to the bottle neck 1 by means of a metal strap 23 whose upper end is bent upon an annular recess 24 formed in the top edge of the casing 14 and whose lower end is bent beneath the shoulder 2 of the bottle neck 1, as is usual with closures of this kind.

The operation of this closure is as follows: As the bottle is inverted in an inclined position, as shown in Fig. 9 of the drawing, the glass ball 13 falls by its own weight upon the hard-metal sheet 20 as guided in its movement by the teeth 19, thereby loosening the plane valve 9 which will also fall and withdraw from its seat 7 thereby opening the opening 8 wherethrough the liquid 3 from the bottle 1 will be free to flow, and the liquid will then pass about the ball 13 and towards the segment-of-a-circle shaped hollow spaces 25 (Fig. 2) formed between the four straight sides of the metal sheet 20 and the inner cylindrical surface of the casing body 14 and extending between two ribs 17 and projecting downwardly from the lower face of the top horizontal portion of the casing 14, the liquid then passing from said hollow spaces 25 into the inner hole of the raised mouth 16, as indicated by the arrows in Fig. 9.

By reason of the obturation of the mouth 16 by the central portion of the hard-metal sheet 20, it is impossible to perforate this sheet with a sharp instrument for the purpose of making a central opening for the insertion of a wire to hold the valve 9 and to keep it raised on its seat 7, and it will be very difficult to cause a wire to pass through the sinuous passageway formed by the segment-shaped hollow spaces 25, firstly towards the periphery of the casing 14 and then towards the inner space of the valve-carrier body 4 to engage the valve 9, which operation will also be prevented by the annular flange 5 of the valve-

carrier body 4, which flange 5 is positioned quite near the teeth 19.

Instead of the metal strap 23, the casing 14, which is as a rule made of a plastic material, might be of a diameter slightly smaller than the bottle neck 1, as shown in the modified form of casing 14' shown in Figs. 10 and 11 of the drawing, so that the casing 14' would be provided with a cylindrical extension 26 having its upper edge secured to the lower edge of the body 14' through a horizontal annular flange 27 and its lower edge 28 may be bent beneath the shoulder 2 of the bottle neck 1 by applying heat with a suitable sealing apparatus to soften the plastic material at said place.

It is obvious that changes may be made within certain limits in the construction details of the closure parts, without thereby altering the essential character of the invention which is such as claimed hereinafter.

What I claim is:

1. A closure for an unrefillable container of the type having a neck formed at the upper end thereof comprising a cylindrical valve-carrier body made of plastic material and completely fitted within the container neck, said body being open at the top thereof and closed inferiorly by a bottom having a central opening therein, an upper horizontal flange formed outwardly of the body to rest on the top edge of the neck of the container, a top rim formed upwardly from the flange, a disc valve normally sealing the hole in the bottom of the valve-carrier body, a ball within said body normally resting on the disc valve, a plastic cylindrical casing having a top horizontal portion with a cylindrical outlet mouth portion of reduced diameter projecting upwardly and centrally thereof, four radially extending crossed ribs formed on the lower surface of said horizontal portion, teeth projecting downwardly from the interior ends of the ribs to retain the ball, a hard-metal square sheet resting on the top rim of the valve-carrier body between said rim and the lower surfaces of the crossed ribs to define segmental sheet outlet passageways between each of its four sides and the inner periphery of the casing, said sheet having openings therein through which the rib teeth extend and a metallic strap securing the casing to the neck of the bottle to prevent removal of the closure and violation of said sheet.

2. A closure for an unrefillable container as claimed in claim 1, including lugs projecting upwardly from the inner edges of the openings of the hard-metal sheet, said lugs adapted to flushly fit recesses formed vertically in the periphery of the outlet mouth of the casing and respectively in alignment with the crossed ribs, said sheet obturating the outlet passageways sufficiently to prevent violation of the closure via the outlet mouth and yet permit the flow of liquid from the container out of said passageways and said mouth.

RICARDO MORE BERNAL.
